INVENTOR
W. G. KING

UNITED STATES PATENT OFFICE.

WALTER G. KING, OF NEW YORK, N. Y., ASSIGNOR TO AMERICAN OPTICAL COMPANY, OF SOUTHBRIDGE, MASSACHUSETTS, A VOLUNTARY ASSOCIATION OF MASSACHUSETTS.

EYE PROTECTOR.

Application filed December 9, 1922. Serial No. 605,922.

To all whom it may concern:

Be it known that I, WALTER G. KING, a citizen of the United States, residing at New York, in the county of New York and State of New York, have invented certain new and useful Improvements in Eye Protectors, of which the following is a specification.

This invention relates to improvements in eye protectors and has particular reference to a novel and improved construction of protector for use in the industries.

One of the principal objects of the present invention is the provision of a device of this character which shall satisfactorily protect the eyes from flying particles, as from grinding wheels, and the like, and at the same time permit of free and clear lateral vision when the protector is in position on the face.

A further object of the invention is the provision of a device for the accomplishment of these results, which shall be of very strong and durable construction, but light in weight, and in which use of frangible glass, or the like, is reduced to a minimum.

Other objects and advantages of the invention include the simplification and improvement in details of construction and manufacture, and should be readily apparent by reference to the following specification taken in connection with the accompanying drawings, and it will be understood that I may make any modifications in the specific details of construction shown and described within the scope of the appended claims without departing from or exceeding the spirit of the invention.

Figure I represents a front view of a protector embodying my improvements.

Figure II represents a plan view thereof.

Figure III represents a sectional view taken as on the line III—III of Figure I.

Figure IV represents a detail view of the screen member expanded.

Figure V represents a view taken as on the line V—V of Figure III.

In the drawings, in which similar characters of reference are employed to denote corresponding parts throughout the several views, the numeral 1 designates the bridge or center of the mounting, which is preferably in the form of a pliable chain which may be twisted to adjust the distance between the eye cup members designated as an

entirety by the numeral 2, the ends of the chain being attached to these cups as by the clips or staples 3. These cups are preferably formed from a moldable composition material which is relatively light, sanitary and may be readily cleansed. The cups 2 are formed at their forward portions with the annular groove or channel as at 5, adjacent which is the rear shoulder 4, against which the lens 6 is seated, the material of the cup adjacent the shoulder 4 being curved around into the rim portion 7 for embracing the edge of the lens and retaining it in place, the lens being preferably either snapped or placed into position against the shoulder 4 and the rim bent down around the lens to firmly secure it in place.

In the particular work for which the present goggle is intended it is desirable that the workman wearing the same have a certain amount of lateral vision, and at the same time the sides must be so enclosed as to keep out flying particles, or the like. To accomplish this result I preferably cut away an appreciable lateral portion of the composition cup, as is indicated at 8, and make use of the screen closure 9 therefor, preferably of a suitable very fine mesh screen. This member is formed with a selvage or finished edge, as at 10, and has the opposite edge as at 11 cut to conform to the shape of the rear of the cup member 2.

In use the screen member having been properly cut is fitted around the exterior of the cup with the selvage 10 abutting the shoulder 4 and making a neat joint therewith, the ends of the screen member overlapping and being pierced by the staple connection 3 which serves to securely attach the screen member around the goggle, as should be best understood by reference to Figures III and V.

In order that the protector may best and most comfortably fit the face and at the same time to cover over the raw or cut edge 11 of the screen material, I preferably provide the finishing channel member 12 in the form of a drawn up ring, or the like, of the same composition material as the cup itself, this member being initially drawn up in ring like formation, the opening of the channel being sufficiently large to receive both the screen 9 and eye cup 2, as shown in Figure III, and being bent to the edge configura-

tion of the cup 2. Having been placed in position the ring is preferably both cemented and pressed, as by heated dies, to cause it to tightly clamp against the eye cup on the one side and firmly adhere thereto to resist any loosening thereof, and on the other side to tightly bind against the screen thus firmly securing it in place and prevent any possible loosening thereof.

10 If desired to further aid in retaining the screen in position, hollow or other rivets such as 14 may be employed, piercing both the cup and the encircling screen and securing said parts together.

15 From the foregoing it will be seen that I have provided a practical, inexpensive and durable eye protector construction, in which the composition cup members serve to secure and retain the lenses in place and the doubled composition rear edge protecting portion provides a soft and satisfactory face engaging member for the protector, and at the same time serves to secure in place the screen covering for the lateral windows or visual 20 apertures of the device.

25 I claim:

1. In a device of the character described, the combination with composition eye cups each having a lateral window, of a screen en-

circling each cup and forming a protection 30 for the window, a composition channel rim overlying the rear edge of each cup and screen and pressed into clamping engagement therewith to secure the parts together, the screen member having its ends overlapping at the inner side of the cup, and a bridge between the two cups having fastening portions extending through the screens and eye cups to secure said parts and the bridge together in a unitary article of manufacture.

2. As an article of manufacture, an eye protector comprising a composition eye cup having an outwardly extending peripheral lens engaging shoulder and an adjacent lens 45 receiving channel, a lens engaging said channel against one side of said shoulder, said eye cup having a lateral window, a screen member encircling the cup and fitting behind the outer portion of the shoulder, the 50 screen member overlying and providing a closure for the window, a composition channel rim overlying the rear edge of the cup and screen member and cemented in clamping engagement therewith to secure the parts 55 together.

WALTER G. KING.
